UNITED STATES PATENT OFFICE.

FRANK E. HOUSH, OF BOSTON, MASSACHUSETTS.

DESIGN FOR AN ADVERTISING-CARD.

SPECIFICATION forming part of Design No. 33,994, dated January 29, 1901.

Application filed December 19, 1900. Serial No. 40,454. Term of patent 14 years.

To all whom it may concern:

Be it known that I, FRANK E. HOUSH, a citizen of the United States, residing at Boston, in the county of Suffolk and State of Massachusetts, have invented and produced a new and original Design for an Advertising-Card, of which the following is a specification, reference being had to the accompanying drawings, forming part thereof.

Figure 1 is a plan view of an advertising-card, showing my new design. Fig. 2 is a sectional view on line 2 2 of Fig. 1.

As shown in the drawings, the leading or material feature of my design consists in an advertising-card rectangular in outline and provided with an oval space *a* and a square space *b*, substantially as shown in the draw-

ings, the oval being recessed or depressed below the general surface of the card, while the square is elevated above the general surface 20 of the card. This feature of elevation and depression of the two elements of my design is shown most distinctly in Fig. 2. Around and surrounding these oval and square surfaces is the plane surface of the card *c*. 25

Having described my invention, what I claim as new, and desire to secure by Letters Patent, is—

The design for an advertising-card, as herein shown and described.

FRANK E. HOUSH.
